UNITED STATES PATENT OFFICE.

OTTO KLEIN, OF PATERSON, NEW JERSEY.

SELF-INDICATING TARGET.

1,100,246.

Specification of Letters Patent. Patented June 16, 1914.

Application filed October 15, 1913. Serial No. 795,178.

To all whom it may concern:

Be it known that I, OTTO KLEIN, a subject of the German Emperor, residing at Paterson, in the county of Passaic and State of New Jersey, have invented certain new and useful Improvements in Self-Indicating Targets, of which the following is a specification.

The present invention relates to targets of the kind described and shown in my United States Letters Patent No. 1072621, issued September 9, 1913, and has for its object to provide a more simplified structure.

My invention is illustrated in the accompanying drawing in which similar reference characters denote corresponding parts and in which—

Figure 1 is a front elevation of the target with the front cover removed and Fig. 2 is a cross section on line 2—2 of Fig. 1. Figs. 3, 4 and 5 are detail views.

In the drawing, which forms a part of this specification, *a* denotes a box or casing of rectangular cross section in which the target is arranged and which has an open front adapted to be normally closed by a cover *a*² which is provided with a circular hole *a*³ of the size corresponding to that of the target disk.

The target proper consists of a circular disk composed of a number of individual concentric parts *b*, *b'*, *b*², *b*³, *b*⁴, *b*⁵, *b*⁶, which form separate sections capable of movement independently of one another.

Fixed to the side walls of and within the casing is a cross spindle *c* on which are loosely mounted two sets of bars *e*, *f*, there being as many bars in each set as sections of the target. The two bars for each section are fixed to the rear and at opposite sides of each section and at points located in a horizontal central line of the target disk. The bars at their lower end are spread or bent laterally, as at *e*², *f*², so as to permit the use of wide number plates, and one bar of each section is hook-shaped as at *e*³, adapted, as will be later explained, to engage a number plate corresponding to the section of the respective bar, while the other bar *f* of the same section serves as a counter-balancing means whereby the section when struck will receive unison of movement.

In the present embodiment of my invention, each of the bars *e* and *f* are composite bars, *i. e.* it consists of two sections joined to one another at their upper points by

rivets *e*⁴, *f*⁴ and at their lower points by metal plates *g*. The central part or bull's eye of the target has only the composite bar *e*, *e*² (Fig. 2) of which the section *e* extends straight down instead of being bent as the other bars are at *e*². By this suspension mechanism each section of the target is capable of a movement in horizontal direction independently of the others, and by virtue of the double suspension at opposite ends its movement will be uniform. Extending at the lower end of the casing and transversely therethrough is a spindle *h* on which are suitably mounted a plurality of angular plates *i* which in number correspond to that of the sections of the target disk. These plates are pivoted or hinged on the spindle so as to be capable of freely turning thereon and are disposed in a horizontal row adjacent to one another. On the outer surface of each plate certain numbers or figures are printed, embossed or otherwise applied, which numbers are adapted to indicate the distance or the number of the sections from the bull's eye.

Normally, that is when the individual sections of the target are in their projected forward position, the plates *i* are raised so as to rest with their lower edges on the hook-shaped ends of the bars *e*, as shown in Fig. 2. When, however, while shooting, a section of the target is struck, the latter is caused to slightly move rearwardly whereby the hook-shaped bar *e* of the struck section releases the corresponding number plate *i* which by its own weight will be caused to swing around the spindle *h* into vertical position, exposing its number through a hole *a*⁴ in the cover *a*² and indicating the distance of the section from the bull's eye.

To return the released number plates to their normal position, that is into engagement with the corresponding hooked bars *e*, I provide a finger *j* for each plate *i*, which fingers are fixed to the spindle *h* and are adapted when turned with the latter to engage the upper or inwardly bent portions *i'* of the corresponding plates so as to swing the latter inwardly and upwardly into engagement with the corresponding hooked bars *e*.

For the manipulation of the spindle *h* I provide a crank lever *h'* secured to or integral with the spindle *h* which lever projects rearwardly into the casing and is connected to a spring *h*² secured to the bottom of the

- casing. This spring tends to constantly draw the arm h' downwardly in which position the fingers j are disengaged from the number plates. Pivottally connected to the 5 rear end of the lever h' is a bar h^3 which is adapted to project outwardly from the casing through a slot (not shown) in the cover a^2 and to which bar a cord or wire (not shown) may be attached.
- 10 The bars e and f are arranged in an inclined position relative to the vertical plane, so that by the displacement of the corresponding section they will by their own gravity cause the return of the displaced 15 disk into normal position. The cross bar a' extending through the casing below the center of the sections of the target disk and behind the latter serves as a stop limiting the forward and rearward movements of the 20 target sections. The bars e and f may be spaced apart by pins k passed through loops e^a, f^a formed at the upper ends of the bars e and f which pins are driven into the rear wall of the casing.
- 25 The lateral swinging movement of the target sections may be limited by pins a^5 projecting rearwardly from the cross bar a' between the sets of bars e and f .

What I claim and desire to secure by Letters Patent is:

1. In a target, the combination with a target disk, composed of individual concentric sections, of a horizontal spindle, sets of suspension bars rotatively borne on said spindle and connected to the said target sections, 35 said bars being spread or bent laterally at their lower ends and the bars of one set having hooks, and freely and independently movable number plates one for each target section, said number plates being adapted to 40 be normally engaged by said hooked bars.
2. In a target, the combination with a sectional target disk, of suspension members having hook-shaped ends, a spring actuated spindle, freely movable number plates thereon, one for each target section adapted to 45 normally rest on the hook-shaped ends of said suspension levers, and manually operated fingers on said spindle adapted to engage said number plates to reset the latter. 50

In testimony whereof I affix my signature in presence of two witnesses.

OTTO KLEIN.
